UNITED STATES PATENT OFFICE.

WILLIAM B. SHEARER, OF NEW YORK, N. Y., ASSIGNOR TO INTERNATIONAL TORPEDO BOAT CORPORATION, OF WILMINGTON, DELAWARE, A CORPORATION OF DELAWARE.

BOAT.

Application filed May 21, 1920. Serial No. 383,170.

To all whom it may concern:

Be it known that I, WILLIAM B. SHEARER, a citizen of the United States, residing in the city, county, and State of New York, ⁵ have invented certain new and useful Improvements in Boats, of which the following is a specification.

In my application for Patent No. 206,407, filed December 10, 1917, I have disclosed a ¹⁰ torpedo boat having a space forward just sufficient in length to accommodate a torpedo, the deck above this space being adapted to open to permit introduction of the torpedo, and the space adapted to be flooded ¹⁵ with sufficient water to support the torpedo so that it may be launched by propelling it through such water under its own power. My present application provides certain ²⁰ improvements on the boat described in the above application and other applications (chiefly No. 273,850, filed January 29, 1919) of mine referring to details of the same boat. An important feature of the present boat is that it is well ²⁵ adapted for use as a launch in peace time, and in war time is adapted to carry more than one torpedo and more powerful engines and to produce a speedier and more seaworthy boat altogether. Various other ³⁰ features of advantage are referred to in detail hereinafter and the novel points are covered in the claims.

The accompanying drawings illustrate an embodiment of the invention.

³⁵ Fig. 1 is a side elevation of the boat equipped as a launch for use in times of peace;

Fig. 2 is a plan, with the roof of the closed cockpit removed and Fig. 3 is a longitudinal section of the boat equipped for war use;

Figs. 4, 5, 6 and 7 are cross-sections on the correspondingly numbered lines of Fig. 3.

⁴⁵ Referring to the embodiment of the invention illustrated, the main cockpit or cabin 1 is located in the center of the length of the boat with a tight deck 2 and a glass front 3 and a rear end 4 in which is a door ⁵⁰ communicating with a fair-weather cockpit 5, which may carry an awning 6, Fig. 1, preferably not when in action since concealment is to be desired. The operator has his seat 7 in the open cockpit and a steering wheel 8, besides the steering wheel 9 within

the closed cabin, these two being connected to the rudder by any usual or suitable gearing. A pair of gasoline motors 10 are arranged in the cabin, one on each side, and drive the shafts 11 of twin screws and also ⁶⁰ drive pumps 12.

The boat has a forward space 13 of just sufficient length to accommodate one torpedo and adapted to be flooded with sufficient water to support the torpedo so that the latter may be propelled through such water under its own power and thus launched, as explained in detail in connection with my aforesaid applications. A bow section 14 is hinged at 15 and connected ⁶⁵ by an arm 16 and link 17 to a rod 18 which runs to the operating compartment so that the operator can swing this bow section up when a torpedo is to be launched. The water then fills the torpedo space. Its level ⁷⁰ is as indicated at 19 when the boat is loaded and at rest, and when the bow is opened the level rises to the point 20 so as to fill the launching space. The torpedo A runs on rollers 21 and is held by a T-piece 22 in ⁷⁵ overhead guides 23 which extend through the launching compartment and into the bow section as shown. It is held against longitudinal movement until it is to be launched, whereupon the holding means are ⁸⁰ withdrawn and a trigger operated to start its motor, these operations being controlled from the operator's cabin and being illustrated and described fully in my aforesaid applications. Above the main deck 24 of ⁸⁵ this compartment is a supplementary deck 25 providing an air space, which can also be used for stowage of various equipment by making the transverse brace 26 as a watertight bulkhead with a stuffing box ⁹⁰ for the passage of the rod 18. The transverse brace 27 is open to permit the operation of the link 17 which passes through it, and the removable bow section passes up into the forward part of the space enclosed ⁹⁵ by this supplementary deck.

Astern of the intermediate compartment and communicating therewith is a third compartment 28 into which the torpedo is initially passed. The length of the several parts is such as to admit of carrying three torpedoes, the first A in the launching compartment, the second B in the intermediate cabin or machinery compartment, and the third C in the reserve or loading compartment. ¹⁰⁵ ¹¹⁰

ment. It is intended that the boat shall carry ordinarily only the two torpedoes A and C but the intermediate one B may be also carried in special cases. The stern compartment 28 has a deck 29, 30, the central portion of which is a swinging hatch 31, Fig. 4, which can be opened to permit the lowering of the torpedo directly on to the supporting rollers 32. The part 30 of 10 the afterdeck constitutes the floor of the open cockpit 5, and the seat 7 overlying it is arranged also to swing up and out of the way as shown in Fig. 4. Fuel tanks 33 are located in the stern compartment out of line 15 with the torpedo and racks may be carried on the stern deck at the sides of the hatch for supporting depth bombs 34, and various other articles of equipment may be carried below or above deck according to circumstances. 20

The space between the motors 10 (Fig. 5) is sufficient to accommodate the torpedo B and guide rollers 35 are arranged to support it in such position. Communication 25 from the intermediate compartment to the launching compartment is had through a door 36 hinged at one side and fastened, when closed, by the usual clamping bolts at the opposite side. 30

The stern deck being opened a torpedo is lowered directly into position there. It is then shoved forward through the intermediate compartment and the open door 36 into the launching compartment and 35 clamped into position there and the door 36 shut. A second torpedo is introduced and shoved forward to the position B, and a third one similarly introduced and retained in the position C. Or, the second 40 torpedo may be left in the position C and no third torpedo loaded aboard the boat. The torpedo C and also the torpedo B, when one is being carried in this position, are strapped down as indicated in Fig. 4 by means of straps 37 fastened to ring bolts 38 and this will prevent their escaping sideways from their roller track or shifting longitudinally. 45

After the first torpedo is launched the 50 bow section 14 is closed and the pumps 12 used to pump out water through pipes 39 (Fig. 3) from the launching compartment. The latter is quickly emptied, the door 36 opened and a reserve torpedo shoved forward to the launching position. 55

In the intermediate compartment 1 (Fig.

5) there is space at the sides of the motors for berths 40, and the floor is composed of two hinged sections 41 which can be lowered between the motors when there is no torpedo in the way. 60

The described arrangement provides a low light-draft launch which can be built for speed and to carry high powered motors. When unloaded the water line will strike at a point in the rear of the removable bow section and even when fully loaded the draft will be comparatively slight. The storage of fuel is sufficient to give a large 65 cruising radius. Thus while well adapted for pleasure or for use in peace time, she 70 has the qualities of speed, cruising radius, torpedo capacity and comparatively slight visibility which contribute most to efficient use. 75

A gun 42 (Fig. 3) may be mounted in the cockpit 5 and arranged to be elevated to the position shown in dotted lines. Various other usual or suitable articles of equipment may be provided. 80

Though I have described with great particularity of detail a certain specific embodiment of my invention, yet it is not to be understood therefrom that the invention is restricted to the particular embodiment 85 disclosed. Various modifications thereof in detail and in the arrangement of the parts may be made by those skilled in the art without departing from the invention as defined in the following claims. 90

What I claim is—

1. A boat having a torpedo launching space and a reserve torpedo space with an opening through which a torpedo may be introduced directly from outside the boat, said launching space enclosed directly by the hull of the boat and adapted to be flooded with sufficient water to support the torpedo therein so that it may be propelled through such water under its own power. 95

2. A boat having a forward torpedo launching space, a stern reserve torpedo space, an intermediate closed cabin and an open cockpit at the rear of the latter, part of the cockpit overlying said reserve space and constituting a removable deck over said reserve space. 105

In witness whereof, I have hereunto signed my name.

WILLIAM B. SHEARER.
